UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

RAILWAY-CAR CONSTRUCTION

Application filed April 26, 1929. Serial No. 353,304.

The invention relates to railway cars, and more particularly, to means for attaching an end wall structure to a railway car. A very common end wall structure in use comprises a plurality of corrugated or embossed metallic plates secured together along horizontal lines and flanged adjacent their vertical edges, which flanges are secured together and to the upper end lower longitudinal frame members of the car. In such a structure the impact of the shifting cargo against the end wall is carried by the embossments acting as beams to the vertical flanges, which united flanges then become a horizontally loaded vertical beam between the upper and lower longitudinal frame members of the car.

The place of attachment of the flanges of the adjacent plates forms a weak spot in the above mentioned vertical beam and it is an object of this invention to reinforce this weak spot with a member which is a splicer, a stiffener and also means for attaching the end wall to the longitudinal frame members of the car. Another object is to so form such an attaching means that it will constitute a very strong vertical beam to resist the horizontal load imposed thereon by the end wall, particularly by the horizontal reinforcing corrugations or embossments, if such are used in the end wall.

Such a means of attachment, or double gusset, will also perform the usual functions of the corner post or end frame member of the car, as it also has considerable column strength. The end post forms a part of the side truss of the car which carries the load of the lading, therefore, my construction is desirable in a car end having the sheets secured together along vertical lines.

In the drawings:

Fig. 1 shows a partial side elevation of a railway car with my invention applied thereto.

Fig. 2 is an end elevation of the same car.

Fig. 3 is a perspective view of the double gusset.

End walls for railway cars now in general use comprise an upper (preferably corrugated) plate 2 overlapping and secured to a lower (preferably corrugated) plate 3 on a

substantially horizontal line 4. These plates are preferably provided with flanges 5—6 adjacent their vertical margins with the flanges 5 of the upper sheet overlapped and secured to the flanges of the lower sheet. These flanges are secured directly or indirectly to the side plate 7 and side sills 8, respectively, so that the end wall and flanges perform the functions of the usual corner post of the car.

The double gusset member 10 is attached to both the upper and lower end wall plates either directly or through the medium of the upper and lower vertical flanges 5—6 and is also secured to the side sill 8 and side plate 7 or other longitudinal frame members of the car (11). The drawings show bolts 12 and rivets 13, respectively, serving this purpose.

The gusset member is relatively narrow adjacent its middle part (15) and relatively wider adjacent its end portions and is preferably provided with a flange 16 at its outer vertical margin which decreases in depth from the middle part of the member toward its opposite ends, respectively.

A series of corrugations 18 transfer an equally distributed load upon the member 10 which, with its double gusset construction, forms a pair of cantilevers to distribute the load to the sill and plate, respectively. If the car is provided with intermediate belt rails 11, part of the load would be distributed to these rails. The outwardly projecting flange 16 stiffens the member as a beam and as a column.

I have shown and described my construction applied to a railway box car but it may be applied to open top gondola cars, stock cars and general service cars, and in fact any type of railway equipment to which a horizontally corrugated or embossed end wall is adaptable.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. Means for attaching a horizontally corrugated end wall of a railway car to the longitudinal frame members of the car comprising a double gusset which is relatively narrow adjacent its middle part and relatively wider adjacent its end portions, said member being secured to said end wall and to said longitudinal frame members at its opposite ends.
- 10 2. Means for attaching a horizontally corrugated end wall of a railway car to the longitudinal frame members of the car comprising a double gusset which is relatively narrow adjacent its middle part and relatively wider adjacent its end portions and provided with a flange at one vertical margin thereof, said member being secured to said end wall at its other vertical margin and to said longitudinal frame members at its opposite ends.
- 15 3. Means for attaching a horizontally corrugated end wall of a railway car to the longitudinal frame members of the car comprising a double gusset which is relatively narrow adjacent its middle part and relatively wider adjacent its end portions and provided with a flange at one vertical margin thereof which decreases in depth from the middle part of the member toward its opposite ends,
- 20 4. In a railway car having upper and lower horizontal frame members, the combination of an end wall comprising two metallic plates joined along a horizontal line and formed with integral horizontal embossments terminating within the plate adjacent a vertical margin thereof, and a member having its opposite ends secured to said frame members respectively with its inner vertical marginal portion secured to the vertical margin portions of said sheets, said member being relatively narrow adjacent the joint between said plates and increasing in width toward its opposite ends.

GARTH G. GILPIN.
